UNITED STATES PATENT OFFICE.

ALBERT J. D. OHM, OF ASTORIA, NEW YORK, ASSIGNOR TO MAX SCHAFER COMPANY.

DESIGN FOR AN ARM FOR LAMP FIXTURES.

Application filed July 23, 1923. Serial No. 6,823. Term of patent 3½ years.

To all whom it may concern:

Be it known that I, ALBERT J. D. OHM, a citizen of the United States of America, residing at Astoria, county of Queens, and State of New York, have invented a new, original, and ornamental Design for Arm for Lamp Fixtures, of which the following is a specification, reference being had to the accompanying drawing, forming part thereof.

The figure is a side elevation of an arm for a lamp fixture.

I claim:—

The ornamental design for an arm for lamp fixtures as shown.

ALBERT J. D. OHM.

Witnesses:

MAX D. ORDMANN,
JOSEPH T. McMAHON.
